HENRY ARTHUR ICKE, OF CHURCH STRETTON, ENGLAND.

CONCRETE DAM.

942,645.

Specification of Letters Patent. Patented Dec. 7, 1909.

Application filed December 31, 1908. Serial No. 470,157.

To all whom it may concern:

Be it known that I, HENRY ARTHUR ICKE, a subject of the King of Great Britain, and a resident of Church Stretton, in Shropshire, England, have invented a new and Improved Concrete Dam, of which the following is a full, clear, and exact description.

The object of the invention is to provide a new and improved reinforced concrete dam of cellular construction, capable of compensating for expansion and contraction due to climatic changes, and open on the upstream side of the dam to form pockets for the reception of the water, to utilize the latter to give stability to the structure and producing direct tensile stresses instead of transverse and compression stresses, thus insuring the desired resistance and providing at the same time suitable overflows or spillways for the surplus water.

In designing reinforced concrete dams, it has hitherto been the practice, while utilizing the water to give stability to the structure, to make them consist of a series of similar cells having a rectangular figure of vertical section transversely to the direction of the stream and with a main reinforcement consisting of bars parallel to the sides of the figure, the pressure of the water thus developing transverse or bending stresses in the slabs forming the roofs of these cells, while no provision was made to eliminate the stresses due to expansion and contraction.

In the present case the concrete dam consists of groups of cells or of pockets with arched roofs and dished floors, while the common partition walls form the straight sides of the pockets, the line of the main reinforcement forming a figure in which direct tensile stresses are developed by the pressure of the water. The roofs of some of the cells of each group are at a higher level than the others and consist of arches without spandrel filling, adapted to compensate for expansion and contraction in the structure, and are hereinafter referred to as the flexible arches and cells. The roofs of the other cells consist of arches with spandrel filling, adapted to be used as spillways for the overflow of water, and are hereinafter referred to as spillway arches and cells.

A practical embodiment of the invention is represented in the accompanying drawings forming a part of this specification, in

which similar characters of reference indicate corresponding parts in all the views.

Figure 1 is a longitudinal sectional elevation of a water way provided with the improvement, the section being on the line 1—1 of Fig. 2; Fig. 2 is partly a cross section of the same on the line 2—2 of Fig. 1 and partly an up-stream elevation. Fig. 3 is an enlarged section of the upper portion of the dam and showing one of the spillways; and Fig. 4 is a similar view of the foundation portion of the dam.

A transverse section of the dam is approximately of a triangular figure, and the cells formed in this construction provide correspondingly shaped pockets open at the upstream side of the dam and to the water. Each of the cells consists of a floor, common side walls and roofs, comprising respectively the base A, diaphragms B and the decking or apron C of the dam. The base A and the decking C are integrally connected with each other at the down-stream angle of the dam and by the diaphragms B. The cells or pockets are arranged one alongside the other, as plainly shown in the drawings. The roofs D of the flexible cells D are raised above those of the spillway cells E, the spandrels of which being filled to the level of the crown of the arches forming the floors of the spillways for the overflow of surplus water. The stilts F on which the flexible arches are carried form the sides of the spillways.

The angle of slope of the decking is determined in each case with regard to economy of construction, taking into consideration the area of the floor, the weight and pressure of the water, the secondary compression stress developed in the decking and the required thickness.

By the arrangement described the arches of the cells D allow expansion and contraction of the dam due to climatic changes, and by having the cells or pockets D and E open at the up-stream side of the dam, it is evident that the said cells or pockets fill with water and the latter is utilized for giving stability to the structure, especially as this part of the water produces tensile stresses in the diaphragms instead of compression stresses, thus insuring the desired resistance in the dam and flexibility in the arches and the diaphragms.

The floor or base A is extended at its lower end to form a water cushion A', and

the bottom of the base A is provided with anchoring devices A² at the lower end of the base A, and its extension, and anchoring means A³ are also formed on the upper end of the base or floor A, as plainly indicated in Fig. 1. It is understood that these anchoring means A², A³ form integral parts of the base A and are embedded in the material constituting the bottom of the water-
10 way in which the dam is located. By the arrangement described, the dam can be carried to any desired height, and the surplus water is taken care of by the spillways formed between the arches of the flexible cells D, as above described and shown in the drawings.

In practice, the diaphragms B need only be of sufficient stiffness to carry the weight of the wall which forms the roof for the 20 cells or pockets D and E. The balanced forces of the pressure of the water and the resistance developed by the walls of the cells or pockets D and E, constitute an effective check to the tendency to vibration caused by 25 the flow of the water over the spillways described and shown.

The metallic reinforcement of the concrete structure is carried out by the use of a main reinforcement consisting of the metallic members G, G' and G², and serving to resist the pressure of the water within the 30 cells. The members G run in straight lines in the diaphragms B and the members G', G² are semicircular or segmental in shape 35 and extend in the base A and roofs C, respectively. The reinforcement member G of one cell is placed in the diaphragm near the face of the next adjacent cell, thus facilitating the location of the members G' 40 and G² farther from the face of the base A and the roof C of the cell, thereby insuring safe resistance to the shearing of the concrete. The curvature of the member G' in the base A of the cell may be made less than 45 a semicircle (see Fig. 4), the horizontal stress being sustained by a reinforcing strut G³ (see Fig. 4) connecting the main reinforcements of adjacent arches at their springings. The same construction may also 50 be applied to the contiguous halves of two adjacent spillway arches, so that the stresses developed at the springings are exactly balanced. The main reinforcements and struts are adapted to either semicircular 55 or segmental arches.

As the pressure of the water is equal on each side of a diaphragm B, it is evident that in the main reinforcement shown and described no transverse or bending stress is 60 developed by the pressure of the water within the cells, except on that portion of the flexible cells D formed by the stilts F on which the arches are mounted. This slight bending stress may be eliminated by lowering 65 the springings of the flexible arches, or

it may be sustained together with the stress developed by expansion and contraction by the cantaliver arms and horizontal pier formed between the springings of the flexible and spillway arches and by the crown of the spillway arch. The upper arm and the side of the pier are strengthened by the auxiliary reinforcing members H and H', as plainly indicated in Fig. 3.

The members G, G' and G² of the main 75 reinforcement form a continuous loop around each cell. The reinforcing members G, G', G², G³, H and H' may consist of any suitable bars of desired size and strength. Small transverse bars may be employed to 80 sustain the stress due to unequal expansion, and to insure against the cracking of the concrete at the surface use is made of fine-meshed fabric reinforcements I, as indicated in the drawings.

Any known method may be employed to 85 render the concrete impervious. The flexible arches may be made of two or more rings with a metal plate or a layer, or a wash of impervious material between them, 90 and as there is a point of contra-strain in each quadrant due to the slight bending action caused by expansion and contraction, no appreciable abrasion or distortion of the material will take place. When the flexible 95 arches are composed of two or more rings, the main reinforcement should preferably be placed near the middle of the outer one and a fine-meshed reinforcement should be placed near the inside and outside surfaces 100 of the rings of the flexible arches.

To prevent leakage in the floor of the 105 dam it may be thickened as shown. The softs of the spillway arches may be flattened and reinforced as shown, and for economic 110 considerations hollow spaces may be formed in the spandrels of the arches, and those in the decking should be closed at the upper end and have small outlets to the downstream side of the dam at their lower ends.

The main reinforcement is distributed longitudinally in the diaphragms B according to stress, and runs in straight lines through them. In the flexible arches the main reinforcement runs in planes at right angles to 115 the axes of the arches, it being understood that a change in the direction of the reinforcement is made by a curve between the springings of the spillway and the flexible arches. To increase the capacity of the 120 spillway, curved or splayed wings may be formed by projecting the stilts of the arches forward upstream, to serve as guides for the water and any solid matter from that may be carried by it.

The spillway arches are of sufficient thickness to prevent appreciable horizontal thrust at the springings, and the diaphragms are stiff enough to carry the weight of the decking when the dam is empty. The dia- 125

phragms B, especially those between the spillway arches, are preferably stiffened by pilasters or they are divided in groined arches and columns.

The proportionate length of the dam occupied by the flexible arches depends upon the length of the spillway required, the range of temperature expected, etc. If the length of the spillway required is small, the number of flexible arches may be increased and their springings brought down to the level of the spillway floor, the stiles being made to form a stiff portion of the flexible arches. If a long proportionate length of spillway is required, the flexible arches may be made greater than a semicircle and the spillway arches made correspondingly stiff.

In order to clearly show the reinforcing members, the thickness of the diaphragms and arches has been exaggerated in the drawings; in practice lighter sections may be adopted. Besides the reinforcements described and shown, suitable bars should be employed to sustain secondary stresses where they occur.

I do not wish to limit myself to the arched spillway cells, as flat-roofed cells reinforced by any suitable system may be used in combination with the flexible arches.

Having thus described my invention, I claim as new and desire to secure by Letters Patent:

1. A concrete dam, comprising a floor, a wall extending integrally from the said floor and inclined in an up-stream direction, and diaphragms connecting the said wall and floor with each other and forming pockets open up-stream.

2. A concrete dam, comprising a floor, a wall extending integrally from the said floor and inclined in an up-stream direction, and diaphragms integrally connecting the said wall and floor with each other and extending vertically and longitudinally for forming pockets open up-stream, to be filled with water for the latter to exert tensile stresses on the members of the dam.

3. A concrete dam, comprising integral members forming pockets open at the up-stream side of the dam.

4. A concrete dam, comprising pockets open only at the up-stream side of the dam.

5. A concrete dam, comprising pockets open only at the up-stream side of the dam and approximately triangular in shape, the base of the triangle forming the floor of the dam.

6. A concrete dam, comprising pockets open only at the up-stream side of the dam and approximately triangular in shape, the base of the triangle forming the floor of the dam, and the floor being extended beyond the apex of the triangle to form an integral water cushion.

7. A concrete dam, comprising pockets

open only at the up-stream side of the dam, the pockets being arranged in series connected with each other by arches.

8. A concrete dam, comprising pockets open only at the up-stream side of the dam, the pockets being arranged in series connected with each other by arches forming spaced spillways for the surplus water.

9. A concrete dam, comprising pockets open only at the up-stream side of the dam, the pockets having a floor, an inclined wall extending integrally from the lower end of the floor in an up-stream direction, and vertical diaphragms integrally connecting the said wall with the said floor.

10. A concrete dam, comprising pockets open only at the up-stream side of the dam, the pockets having a floor, an inclined wall extending integrally from the lower end of the floor in an up-stream direction, the wall being formed at intervals into arches, each arch forming the roof for a corresponding pocket, and vertical diaphragms integrally connecting the said wall with the said floor.

11. A concrete dam, comprising pockets open only at the up-stream side of the dam, the pockets having a floor, an inclined wall extending integrally from the lower end of the floor in an up-stream direction, the wall being formed at intervals into arches, each arch forming the roof for a corresponding pocket, vertical diaphragms integrally connecting the said wall with the said floor, and a plurality of non-arched pockets intervening between adjacent arched pockets.

12. A concrete dam having pockets, one alongside the other and all open only to the up-stream side of the dam, some of the pockets having arched roofs.

13. A concrete dam having pockets one alongside the other and all open only to the up-stream side of the dam, some of the pockets having arched roofs, and a plurality of the remaining non-arched roof pockets intervening between adjacent arched roof pockets, to form spillways having as bottoms the non-arched roofs and as sides the arches of the arched roof pockets.

14. A concrete dam, comprising pockets open only at the up-stream side of the dam and approximately triangular in shape, the base of the triangle forming the floor of the dam, and integral anchoring means on the under side of the said floor.

15. A concrete dam, comprising pockets open only at the up-stream side of the dam and approximately triangular in shape, the base of the triangle forming the floor of the dam and the floor being extended beyond the apex of the triangle to form an integral water cushion, and integral anchoring means on the under side of the said floor and its extension.

16. A concrete dam, comprising integral members forming pockets open at the up-

- stream side of the dam for the water to fill the pockets, and a metallic reinforcement for the said members and encircling the same to eliminate transverse or bending stress developed by the water in the pockets. 5
17. A concrete dam comprising pockets open only at the up-stream side of the dam to fill with water, and a metallic reinforcement in the walls of the pockets and encircling the same to eliminate transverse or bending stress developed by the water in the pockets. 10
18. A concrete dam comprising cells and having a base, diaphragms and a decking, and a metallic reinforcement embedded in the said base, diaphragms and decking. 15
19. A concrete dam comprising cells each having a base, diaphragms and a decking, and a metallic reinforcement formed of continuous members embedded in the said base, diaphragms and decking. 20
20. A concrete dam comprising cells each having a base, diaphragms and a decking, and a metallic reinforcement formed of continuous members embedded in the said base, diaphragms and decking, the members in the diaphragms for one cell being near the face of the diaphragm for the adjacent cell. 25
21. A concrete dam comprising cells each having a base, diaphragms and a decking, a metallic reinforcement embedded in the said base, diaphragms and decking, and an auxiliary reinforcement in the decking of the cells. 30
22. A concrete dam comprising a floor, a wall extending integrally from the said floor and inclined in an up-stream direction, diaphragms integrally connecting the said wall and floor with each other and extending vertically and longitudinally for forming pockets open up-stream to be filled with water for the latter to exert tensile stresses on the members of the dam, and a metallic reinforcement embedded in the said floor, wall and diaphragms for eliminating transverse or bending stress developed by the water in the cells. 35
23. A concrete dam comprising groups of cells having arched roofs, the partition walls common to adjacent cells forming straight sides of the pockets. 50
24. A concrete dam comprising groups of cells or pockets having arched roofs, the partition walls common to adjacent cells forming the straight sides of the pockets, and a metallic reinforcement embedded in the walls of the said cells. 55
25. A concrete dam comprising groups of cells or pockets having arched roofs, the partition walls common to adjacent cells forming the straight sides of the pockets, the roofs of some of the cells of each group being on a higher level than the others to form spillways between adjacent raised roofs. 60
26. A concrete dam comprising groups of cells or pockets having arched roofs, the partition walls common to adjacent cells forming the straight sides of the pockets, the roofs of some of the cells of each group being on a higher level than the others to form spillways between adjacent raised roofs. 65
27. A concrete dam comprising groups of cells or pockets having arched roofs, the partition walls common to adjacent cells forming the straight sides of the pockets, the roofs of some of the cells of each group being on a higher level than the others to form spillways between adjacent raised roofs. 70
28. A concrete dam comprising groups of cells, each group having cells with flexible arches and cells with non-flexible arches. 75
29. A concrete dam comprising cells, some of which have flexible roofs and the adjacent ones have non-flexible roofs. 80
30. A concrete dam comprising cells, sundry of which have raised flexible roofs and adjacent ones have non-flexible lower roofs to form spillways. 90
31. A concrete dam, comprising cells, sundry of which have raised flexible arches, and a plurality of intermediate cells having arches with spandrel filling. 95
32. A concrete dam comprising cells each having a base, diaphragms and a decking, a metallic reinforcement formed of continuous members embedded in the said base, diaphragms and decking, the members in the diaphragms for one cell being near the face of the diaphragm for the adjacent cell, and struts in the said diaphragms. 100
33. A concrete dam comprising cells each having a base, diaphragms and a decking, a metallic reinforcement formed of continuous members embedded in the said base, diaphragms and decking, the members in the diaphragms for one cell being near the face of the diaphragm for the adjacent cell, and struts embedded in the diaphragms for engagement with the base and diaphragm members at their junction. 105
34. A concrete dam comprising cells each having a base, diaphragms and a decking, a metallic reinforcement formed of continuous members embedded in the said base, diaphragms and decking, and struts for the said continuous members and embedded in the lower ends of the diaphragms. 110
35. A concrete dam comprising cells each having a base, diaphragms and a decking, a metallic reinforcement formed of continuous members embedded in the said base, diaphragms and decking, and fine-meshed fabric reinforcements embedded in the base, diaphragm and decking of the cells. 115
36. A concrete dam comprising cells each having a base, diaphragms and a decking, a metallic reinforcement formed of continuous 120

members embedded in the said base, diaphragms and decking, and fine-meshed fabric reinforcements embedded in the base, diaphragm and decking of the cells adjacent to the surfaces thereof.

37. A dam, comprising integral members forming pockets open at the upstream side of the dam for the water to fill the pockets, and continuous metallic reinforces encircling the pockets, and embedded in the walls thereof.

38. A dam comprising a plurality of pockets arranged alongside each other and opening upstream, said pockets being oval in

cross section, and provided with continuous metal reinforces in the walls thereof and encircling the pockets.

39. A dam comprising a plurality of pockets arranged side by side and opening upstream for receiving the water, and closed loops encircling the pockets.

In testimony whereof I have signed my name to this specification in the presence of two subscribing witnesses.
